UNITED STATES PATENT OFFICE.

CHRISTIAN JØRGENSEN, OF COPENHAGEN, DENMARK.

HOMOGENIZING VALVE.

Application filed August 3, 1926. Serial No. 126,920.

Homogenizing valves are known, one part of which consists of a conical body fitted with a supply pipe and, in addition, with a transverse channel about midway, the 5 other part of the valve consisting of a conical casting.

Experience has shown that in certain cases the transverse channel may be omitted and in lieu of that the supply channel may be 10 continued right through, but the discharge opening at the bottom of the valve casing should then be closed.

The modified construction is illustrated on the drawing which shows a vertical longitudinal section of a homogenizing valve. In the following the same reference numerals are used as in the main patent.

15 A is the conical body fitted with a central channel C and finely ground to fit a casing B.

In contradistinction to the construction specified in the main patent, the channel C is here continued throughout the entire body

A where a spreading chamber H is provided. The conical surface of the body A is smooth, 25 and as the parts A and B are pressed against one another at a very considerable pressure the liquid which has to be homogenized, and which is supplied by way of the channel C at a still higher pressure, will be pressed out 30 along the entire surface of the body A.

Having now described my invention, what I claim as new and desire to secure by Letters Patent is:

In a homogenizing valve, a pair of coacting members provided with finely ground elongated and conical coacting engaging surfaces, one of said members having a central delivering bore and the other of said members being provided with a spreading chamber and connecting with the bore and the engaging surfaces, substantially as and for the purposes set forth. 35 40

In testimony whereof I affix my signature.

CHRISTIAN JØRGENSEN.
